Inventor:

James F. Green

UNITED STATES PATENT OFFICE.

JAMES F. GREEN, OF PHILADELPHIA, PENNSYLVANIA.

WOOD-WORKING-TOOL HANDLE.

SPECIFICATION forming part of Letters Patent No. 247,188, dated September 20, 1881.

Application filed July 7, 1881. (Model.)

To all whom it may concern:

Be it known that I, JAMES F. GREEN, a citizen of the United States, residing at 1443 Warnock street, in the city of Philadelphia, and State of Pennsylvania, have invented certain new and useful Improvements in File and Tool Handles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a view of the hollow metal handle, with a square projection or tang pointed, which is in the closed end of the handle, combined with the wooden filling. Fig. 2 is a view of the wooden filling, which is perforated at both ends.

The object of my invention is to provide a handle which will receive and firmly hold a file or tool by its tang, and which can be applied to hold tools and files of various-sized tangs.

My invention consists of a file and tool han-

dle which is hollow for a certain distance straight, and then is chambered the remainder, so as to make it light and not expensive to make or unwieldy to use.

A represents a file or tool provided with a tang, B.

C C represent the hollow metal handle with square projection or tang, C'.

D represents the wood, of any suitable hardness, with small hole E, in which the square projection or tang C enters and securely holds it in position.

F represents a small hole in the wood, in which the tang B enters.

What I claim as my invention, and wish to secure by Letters Patent, is—

A metal shell, C, having internal projection or tang, C', at the closed end, combined with the wooden filling D, having perforations to receive tang, all forming a file and tool handle, substantially as described.

JAMES F. GREEN.
